DESIGN FOR A DINNER DRESS

Germaine Monteil, New York, N. Y.

Application November 6, 1940, Serial No. 96,358

Term of patent 3½ years

To all whom it may concern:

Be it known that I, Germaine Monteil, a citizen of the United States, residing at 955 Fifth Avenue, New York city, in the county of New York and State of New York, have invented a new, original, and ornamental Design for a Dinner Dress, of which the following is a specification, reference being had to the accompanying drawing, forming part thereof.

The trimming shown in the bodice comprises beading embroidery, together with bands of beading at the waist, neckline and sleeve openings.

I claim:

The ornamental design for a dinner dress, substantially as shown and described.

GERMAINE MONTEIL.
